CORNER LOCK

Henry Richardson, Chicago, Ill.

Application October 20, 1932, Serial No. 638,681

9 Claims. (Cl. 5—288)

This invention relates to what are commonly known as corner locks for bedsteads and similar articles of furniture, the same comprising the instrumentalities by which a side rail for a bedstead is separably connected to a bed end.

My present invention is based upon the principle of, and constitutes an improvement on, an earlier invention forming the subject matter of an application for Letters Patent filed by me on the 25th day of August, 1930, Serial 477,536, and the present application constitutes a continuation in part of the aforesaid application.

The corner lock construction forming the subject matter of my aforesaid application Serial 477,536, is characterized by the provision of an angle bracket having a post plate for attachment to the bed end and a projecting flange having an upwardly opening slot formed with an edge downwardly and inwardly inclined toward the post of the bed end, a laterally offset portion of the vertical flange of the side rail being offset into the slot, the offset portion having an edge thereof contacting against the said inclined edge to wedge and hold the adjacent end of the side rail against the post plate, the vertical limb or flange of said rail lying against the inner side of the slotted flange of said post plate.

In my aforesaid application Serial 477,536, I also disclosed another embodiment of the same structural principle wherein, in lieu of the slot in the projecting flange of the bracket, I provided a laterally offset portion of said flange on the inner side of the latter formed with an edge downwardly and inwardly inclined toward the post of the bed and coacting against a laterally offset portion of the vertical flange of the side rail by a downwardly inclined sliding contact therewith.

This latter form of the invention has been carried forward and amplified herein.

Among the objects of the present invention are to provide a simple and efficient bed corner fastening of an improved structure, in which the movable portion consists solely of an angle iron side rail of a bedstead adapted to be wedged and held against a post flange of a bracket on a corner post in either the upright or inverted position of said rail, and to provide an invertible corner bracket adapted for both the right and left hand corner posts of the same bed end, said bracket preferably consisting of nothing more than an L-shaped piece of sheet metal shaped to provide rail locking means. A bracket composed only of an L-shaped member having a deep open ended slot in the portion thereof serving as a side flange has been in general use for some

years, the said slot as is well known making it necessary for the bracket to be made of harder or heavier metal than would otherwise be required. The invertible bracket herein shown has no such slot, and because of this and one other reason, later explained, and having reference only to brackets for any form of arcuated post, it is reliably efficient for any kind of metal bed end when made from sheet metal by a simple stamping process.

In my pending application, Serial 518,329 filed February 26, 1931, I have shown a corner construction in which a vertically disposed wooden side bar is employed in combination with a flattened surface on a round hollow metal corner post, said surface providing a recess which is used to accommodate both a post-engaging portion of a bracket and an end edge portion of said wooden bar, the thickness of the latter providing the necessary width to its bearing against a bed end. The present construction shows a similarly flattened surface on a round post used in combination with an angle bar side rail. In this case only as much of the surface of the post need be flattened as will provide a recess for a portion of the post flange of a bracket entered therein; the rail has its vertical flange wedged against an edge portion of said post flange; the side rail being given its necessary width of bearing against a bed end by wedging its horizontal flange against said post flange; an important advantage of the last-named wedging, as shown in the present construction, being that the post flange of a sheet metal bracket is prevented from bending, under the severe pressure exerted against it because of said wedging, by the entering of a portion of said post flange in said recess. This is the reason previously referred to why the bracket shown in the drawing is reliably efficient not only for square but also for any form of arcuated corner post when made of sheet metal. Another advantage of said recess in combination with an angle side rail is that it enables the horizontal flange of said rail to have a much wider and more efficient bearing against the post flange of a bracket on a round or oval corner post than can otherwise be obtained without the use of hard or heavy metal for a bracket. When the vertical flange of an angle side rail is wedged against the post flange of a bracket and both the inner and outer surfaces of said post flange are arcuated in order to fit the latter against the surface of a round post, as is commonly done, an end edge portion of the horizontal flange must be cut out to permit the described wedging of said

vertical flange against the post flange. A recess in the surface of a round post as shown and described, dispenses with such cut outs, which not only add to the cost of a corner joint, but are also detrimental because they greatly reduce the amount of bearing an end edge of the horizontal flange of an angle bar can have against the post flange of a bracket. When arcuation of the post flange of a bracket for a round corner post is avoided the same bracket becomes adapted for both square and round corner posts, and when it is invertible as shown herein, only one form of bracket is required for all corner posts of any bedstead having metal ends.

15 The structural features and advantages of the present improvement will be more readily appreciated by those skilled in the art from the following detailed description of one practical embodiment thereof illustrated in the accompanying drawing, in which:—

Fig. 1 is an outer side elevation of a fragment of a round bed post, and an invertible corner bracket and angle side rail showing my improved construction as viewed from the left of Fig. 2.

25 Fig. 2 is an end elevation, in section through the side rail, on the line 2—2 of Fig. 1.

Fig. 3 is a top plan view, in horizontal section through the corner post.

30 Fig. 4 is a view similar to Fig. 2, but showing the side rail in endwise reversed and inverted position wherein it is adapted to support bed springs or slats.

Fig. 5 is a perspective view of the corner bracket.

35 Fig. 6 is a perspective view of an angle bar side rail, broken out between its ends.

Referring to the drawing, 10 designates the corner post of the bedstead frame, in this instance shown as a round tubular structure, although a square or other form of post may be used with 40 my improved corner lock.

The corner bracket, shown in detail in Fig. 5, 45 comprises a flat post plate 11, and an integral side plate or flange 12 projecting at a right angle to the post plate 11 from one vertical edge of the latter. The side plate 12 is, in this particular embodiment of the invention, formed with a laterally and outwardly bent portion 12' for a purpose later described. On the inner side of this portion 12' are a pair of wedge members 13 and 50 14 preferably formed as an offset portion of 12' disposed with their inner ends continuous with each other and oppositely inclined, as shown in Figs. 1 and 5. The wedge member 13 presents an edge 13' that is downwardly and inwardly inclined in one upright position of the corner bracket, and the other wedge member 14 has a 55 similar edge 14' that is similarly inclined in the inverted position of the bracket. It may here be explained that by the expression "inwardly inclined" I mean inclined toward the post plate 11 of the bracket.

The outer face of the post plate 11 is provided 60 with rail holding means consisting of a pair of vertical stop lugs 15 and 16, preferably constituted as shown, by offset portions of the plate 11 and spaced from the side plate 12 distance sufficient for said lug to overlap the inner surface of the vertical limb of the side rail that engages the bracket, for a purpose later described. Manifestly the lugs 15 and 16 may be continuous with 65 one another, but are preferably spaced apart because if made continuous, a notch would be necessary in the horizontal flange of the side rail adjacent its vertical flange to permit the wedg-

ing of the side rail against the post plate in its inverted position, as shown by Fig. 4.

The movable portion of the present corner joint consists solely of an angle iron side rail, as shown, having its vertical limb adjacent the 80 inner side of the side plate 12, said vertical limb being identified by 17 and the horizontal limb by 18. The vertical limb 17 has a portion thereof outwardly offset at 19, the offset portion having oppositely inclined edges 19a and 19b that may meet at their inner ends. When the side rail is engaged with the bracket in the upright position of the side rail shown in Figs. 1, 2 and 3, the inclined edge 19b of the offset portion 19 slidingly engages with the inclined edge 13' of the bracket wedge member 13 to wedge and hold an end edge of the side rail against the post plate 11 of the bracket.

When the side rail is reversed endwise and inverted, the inclined edge 19a of the offset portion 19 at the other end of the side rail similarly slidingly engages with the inclined edge 13' to produce the same effect, as shown in Fig. 4. The inclination from the vertical of the wedging edges 13' and 14' is substantially the same as the inclination of the wedging edges 19a and 19b. The edges 19a and 19b are substantially perpendicular or square to the outer surface of the limb 17.

The post plate 11 is secured rigidly to the corner post 10 by the usual short bolts or rivets indicated at 20, supplemented by the usual backing plate or strip 21 within the post. To provide an extended surface contact of the post plate 11 with the hollow round post 10, a localized area of the surface of the post 10 is flattened, as shown at 10' 105 in Fig. 3, which avoids the necessity of transversely curving the post plate 11 to fit a correspondingly curved area of the post 10. Several other important advantages of a flat surface on a round post in combination with an angle iron 110 side rail have already been mentioned.

The end portion of the side rail in the upright position of the latter, shown in Figs. 1 and 2, is engaged with the bracket by simply entering it above the latter and then lowering it. The end 120 portion of the side rail, when in the inverted position shown in Fig. 4, is engaged with the bracket by entering it endwise into the latter with the square end of the transverse limb 18 slightly below the upper bolt or rivet 20, and then lowering 125 it. It will be observed that by locating the bracket wedging members 13 and 14 in the intermediate vertical portion of the bracket side plate, and spacing the attaching rivets or bolts 20 sufficiently apart, the necessity of notching out the end 130 edge of the horizontal limb 18 of a side rail so as to clear the upper rivet 20 when applying the side rail to the bracket in the inverted position of the side rail is avoided, and the end of the horizontal limb is thus given a continuous fit 135 throughout its full width against the post plate of the bracket, whereby more effective resistance to angular side strains on the side rail is obtained, thereby making practical the use of a sheet metal bracket in lieu of a heavy hard metal bracket.

When the side rail has been fully engaged with the bracket, the lug 15, in one position of the bracket, locks the side rail against inward lateral displacement from the side plate of the bracket, and in the inverted position of the bracket, the lug 16 performs the same function.

A noteworthy feature of the invention resides in the invertible character of the bracket, with its duplicate side rail wedging and locking lugs above described. This renders the bracket 150

adaptable for both the right and left corner posts of the bed ends. With the bracket in the position shown in Figs. 1, 2, 3 and 4, the inclined edge 13' of the wedging member 13 constitutes

and, when the side rail is inverted and turned end for end, the said edge of the other offset portion having a sliding engagement with said wedging member adapted to wedge and hold the side rail against the post flange.

80

5 the active wedging member. In the inverted position of the bracket, manifestly the inclined edge 14' of the wedge member 14 constitutes the active wedging member. And in the upright position of the side rail shown in Figs. 1, 2 and 6, the 10 inclined edge 19b constitutes the cooperating active wedging member, while in the inverted position of the side rail shown in Fig. 4, the inclined edge 19a constitutes the active wedging member.

15 Manifestly changes may be made in the specific forms, construction and arrangement of the parts of the bed corner joint herein shown described, within the principle of the invention. Therefore, it is to be understood that I reserve 20 any modifications falling within the spirit and purview of the claims.

I claim:

1. A bedstead corner fastening comprising a movable portion consisting solely of an angle iron side rail, and a bracket portion, comprising a post flange adapted for attachment to a corner post, a side flange at the outer side of the post flange and at right angles thereto, and a wedging member on the inner side of said side 25 flange projecting laterally thereof, the side rail having its vertical flange adjacent the side flange and on the inner side thereof, and having a portion of the vertical flange offset therefrom, the offset portion having an edge which is substantially square to the outer surface of the vertical flange, said edge coacting against the wedging member by an inclined sliding contact, adapted to wedge and hold the adjacent edge of the side rail against the post flange of the bracket 35 portion.

2. A bedstead corner fastening comprising a movable portion consisting solely of an angle iron side rail, and a bracket portion, comprising a post flange adapted for attachment to a corner post, a side flange at the outer side of the post flange and at right angles thereto, and a wedging member on the inner side of said side 45 flange projecting laterally thereof, the side rail having its vertical flange adjacent the side flange and on the inner side thereof and having a portion of the vertical flange offset therefrom, the offset portion having an inclined edge which is substantially square to the outer surface of the vertical flange, said edge coacting against the 50 said wedging member to wedge and hold the adjacent end of the side rail against the post flange of the bracket portion.

3. A bedstead corner fastening comprising a movable portion consisting solely of an angle iron side rail, and a bracket portion, comprising a post flange adapted for attachment to a corner post, a side flange at the outer side of the post flange and at right angles thereto, and a wedging member on the inner side of the side flange 60 projecting laterally thereof, the side rail having its vertical flange adjacent to the side flange and on the inner side thereof, opposite end portions of the vertical flange being outwardly offset therefrom, each of said offset portions having an edge which is substantially square to the outer surface of the vertical flange, the said edge of one offset portion having a sliding engagement with said wedging member adapted to wedge and hold the side rail against the post 65 flange in the upright position of the side rail,

4. A bedstead corner fastening comprising a movable portion consisting solely of an angle iron side rail, and a bracket portion, comprising a post flange adapted for attachment to a corner post, a side flange at the outer side of the post flange and at right angles thereto, and a wedging member on the inner side of the side flange projecting laterally thereof, said member having an edge portion downwardly inclined toward the bed post, the side rail having its vertical flange adjacent to the side flange and on the inner side thereof and having a portion of the vertical flange offset therefrom, the offset portion having upper and lower oppositely inclined edge portions, one coacting against the downwardly inclined edge of said wedging member 70

to wedge and hold the adjacent end of the side rail against the post flange in the upright position of the side rail, and the other coacting against the downwardly inclined edge of the 75 wedging member on the side flange at the opposite end of the bedstead when the side rail is inverted and turned end for end, and a stop lug on the bracket portion overlapping the inner side of the vertical flange of the side rail in both 80 the upright and inverted positions of the latter.

5. An invertible corner bracket for bedsteads, adaptable to either the right or left hand corner post of a bed end, said bracket comprising a plate, a portion whereof is adapted for attachment to a said post, the remaining portion projecting from the bed end to constitute a side flange provided with a pair of oppositely inclined rail wedging edges, one of said inclined edges co-acting with means on a side rail to connect 85 the latter to the bracket when the bracket is attached to the corner post at one side of a bed end, and the other inclined edge similarly co-acting with means on a side rail when the bracket is inverted and attached to the corner post at 90 the opposite side of the same bed end.

6. An invertible corner bracket for bedsteads, adaptable for attachment to either the right or left hand corner post of a bed end, said bracket comprising a post flange adapted for attachment to a corner post, a side flange at the outer side of the post flange and at right angles thereto, and oppositely inclined members on the inner side of the side flange projecting inwardly therefrom, an inclined edge of one of said members 100 coacting with means on a side rail to wedge and hold the latter against the post flange when the bracket is attached to the corner post at one side of a bed end, and an inclined edge of the other member similarly coacting with means on a side rail when the bracket is inverted and attached to the corner post at the opposite side of the same bed end.

7. An invertible corner bracket for bedsteads, adaptable to either the right or left hand corner post of a bed end, said bracket comprising a plate, a portion of which is adapted for attachment to a said post, the remaining portion projecting from the bed end to constitute a side flange having offset portions thereof, the offset 110 portions having oppositely inclined edges, one of said edges converging downwardly toward a corner post and coacting with means on a side rail to connect the latter to the bracket when the bracket is attached to the corner post at one 115 side of a bed end.

side of a bed end, the other of said edges similarly converging and coacting with means on a side rail when the bracket is inverted and attached to the corner post at the opposite side of the same bed end.

5 8. A bedstead corner fastening comprising a movable portion consisting solely of an angle bar side rail, and a bracket portion comprising a post flange adapted for attachment to a corner post, a side flange at the outer side of the post flange and at right angles thereto, and a wedging member on the inner side of the side flange projecting laterally thereof, the side rail having its vertical flange adjacent to the side flange and on the inner side thereof and having a portion of the vertical flange offset therefrom, the offset portion having upper and lower oppositely inclined edges which are substantially square to the outer surface of the vertical flange, one of said edges coacting against the said wedging member to wedge and hold the adjacent end of the side rail against the post flange in the upright position of the side rail, and the other simi-

larly co-acting against the wedging member on the side flange at the opposite end of the bedstead when the side rail is inverted and turned end for end and a stop member on the bracket portion overlapping the inner side of the vertical flange of the side rail in both the upright and inverted positions of the latter.

9. An invertible corner bracket for bedsteads adaptable to either the right or left hand corner post of a bed end, said bracket comprising a plate, a portion of which is adapted for attachment to a corner post, the remaining portion projecting from the bed end to constitute a side flange a portion of which is offset therefrom, said offset portion being adapted to co-act with means on a side rail to connect the latter to the bracket when the bracket is attached to a corner post at one side of a bed end and to similarly co-act with means on a side rail when the bracket is inverted and attached to the corner post at the opposite side of the same bed end.
